UNITED STATES PATENT OFFICE

162,413

SCREEN GUARD

Clarence W. Jorgensen, Chicago, Ill., assignor to Superior Fastener Corporation, Chicago, Ill., a corporation of Illinois

Application January 25, 1950, Serial No. 7,537

Term of patent 14 years

(Cl. D54—2)

To all whom it may concern:

Be it known that I, Clarence W. Jorgensen, a citizen of the United States, residing at Chicago, in the county of Cook and State of Illinois, have invented a new, original, and ornamental Design for a Screen Guard of which the following is a specification, reference being had to the accompanying drawing, forming a part hereof.

Fig. 1 is a perspective view of a screen guard, showing my new design, the door, in broken lines, is for illustrative purposes only.

Fig. 2 is a front elevational view; and

Fig. 3 is a top plan view.

I claim:

The ornamental design for a screen guard, substantially as shown and described.

CLARENCE W. JORGENSEN.
